AMUSEMENT RIDING APPARATUS

Raymond R. Walker and George S. Hahne,
Follansbee, W. Va.

Application July 1, 1939, Serial No. 282,531

2 Claims. (Cl. 272—44)

This invention relates to rotary, passenger carrying, amusement riding devices.

One of the objects of the invention is to provide an amusement riding device in which the passenger cars are vertically reciprocated during their rotary movement.

Another object of the invention is to provide in association with the apparatus a visible rotating element which may be utilized to ascertain which of the several passengers riding on the device is entitled to an award, as a free ride on the device.

Another object of the invention is to provide in association with the apparatus means for displaying advertising matter, rotary movement being imparted to the advertising means, so as to readily attract the attention of observers.

Another object is to provide an amusement riding apparatus of the character mentioned which is comparatively inexpensive, simple in construction, and readily assembled and dismantled for transportation to lend portability.

Other objects and advantages not hereinbefore specifically pointed out will appear from the following detailed description and the accompanying drawings, in which—

Figure 1 is a side elevational view of the device;

Figure 2 is an enlarged sectional view taken on line 2—2 of Fig. 1;

Figure 3 is a sectional view taken on line 3—3 of Fig. 2;

Figure 4 is a vertical sectional view of the apparatus with the passenger cars and their supporting arms removed;

Figure 5 is an enlarged sectional view taken on line 5—5 of Fig. 4;

Figure 6 is a sectional view taken on line 6—6 of Fig. 5;

Figure 7 is a fragmentary view, partly in section, of one of the passenger cars illustrating the manner of its suspension;

Figure 8 is a sectional view taken on line 8—8 of Fig. 7;

Figure 9 is a fragmentary top plan view of the revolving canopy; and—

Figure 10 is a detailed sectional view taken on line 10—10 of Fig. 4.

Referring to said drawings, the reference numeral 1 designates upright angle irons forming a pedestal on which the apparatus is supported, said pedestal having a base 2.

Journalized in roller bearings 3 located in the center of the base 2 is the lower end of a vertical shaft 4, said shaft being adapted to be driven by any appropriate means, as by the pulley 5. Roller

bearings 6 for the power shaft 4 are provided in the plate 7 of the pedestal, said power shaft protruding through the plate 7 and terminating at a spaced distance above the latter, as shown in Fig. 4.

The power shaft 4 at a short spaced distance above the plate 7 is squared, as shown at 8. Two axles 9, having longitudinal slots 10, are received about the squared portion 8 of the power shaft, as best shown in Fig. 2. One axle is spaced below the other on the drive shaft and said axles are disposed at right angles to each other. Pivot pins 11 attach each axle 9 to the power shaft and permit each axle to be freely rocked about its pivot pin. The opposite ends of each axle 9 is reduced and accommodates a roller 12 designed to be supported by an undulated circular track or race 13 attached to the plate 7.

Angularly disposed studs 14 project outwardly from the upper surface of each of the axles at a point interiorly of the circumference of the track 13, and encircling each stud is the lower flanged end of an ornamental tubular car supporting arm 15. The opposite ends of the flanges provided on the lower ends of the car supporting arms 15 project outwardly beyond the axles 9 and said arms are rigidly fastened to the axles by U-bolts 101. The arms 15 may be appropriately decorated or illuminated, as by colored electric lamps 100. Spaced parallel tie rods 16 connect oppositely disposed arms 15 and afford rigidity thereto. The outer free ends of each arm 15 has suspended therefrom a passenger car 17, as will hereinafter be specifically described.

Manifestly, when the power shaft 4 is rotated, the axles 9 will be rotated therewith, and, as the rollers 12 traverse over the track 13, the ends of the axles, together with the thereto attached arms 15, are rocked about their pivot pins 11 because of the presence of the undulations on the track surface, thereby causing the passenger cars 17 to be likewise rocked or alternately raised and lowered. Obviously, the undulations of the track must be designed so that when one of the ends of an axle 9 is being elevated, the opposite end is being lowered, and vice versa.

The car supporting arms 15 are attached to the axles 9 at a point inwardly of the track 13 to locate the center of gravity adjacent the center of the apparatus to prevent tipping of the apparatus and to substantially eliminate vibration during operation.

Encircling the upper extremity of the power shaft 4, as specifically shown in Fig. 6, is a tubular extension shaft 18 whose upper end terminates

with an attached sphere 193 or other appropriate decorative object. The lower end of the extension shaft 18 is embraced by a collar 19, and the collar 19, as well as the extension shaft 18, are together fixed to the power shaft 4, so as to be rotatable therewith, by a set screw 20. The extension shaft 18 is provided with an annular flange 21 directly above the collar 19.

Freely rotatable on the extension shaft 18 is a substantially conical, hollow, object 22, hereinafter referred to as a "top". The top has an axial sleeve 23 attached thereto by set screws 24 and the sleeve 23 encircles the shaft 18 and is freely rotatable with respect thereto. The lower end 15 of the sleeve 23 is increased in thickness and is designed to rest upon and be supported by the flange 21 of the shaft. Ball bearings 25 in suitable races are provided between the flange 21 and the end of the sleeve 23 so as to facilitate 20 free rotation of the latter on the shaft 18.

The outer periphery of the enlarged lower end of sleeve 23 is serrated, as shown in Fig. 5, and the serrations are embraced by a ring 26 which receives its support from the flange 21. Ball 25 bearings 27 in suitable races are interposed between the flange 21 and ring 26. A spring pressed cylindrical roller 28 is provided in the space between each of the serrations. The ring 26 and cylindrical rollers 28 are maintained in 30 position by a retaining collar 29 which is fixed to the sleeve 23 by set screw 30.

Projecting downwardly through an aperture in the collar 19, or from a projection formed integrally therewith, is a small shaft 31 which has a lever arm 32 fixed to its lower end. A spiral compression spring 33 encircles the shaft 31 and has one end fixed to the outer end of the lever 32 while the opposite end is attached to the collar 19. Pinned to the upper end of the shaft 31 is an arm 38 whose outer free end is provided with a roller 34, the roller being provided on the upper surface of the arm. The roller 34 is designed to contact a lever 35 which projects outwardly from and is formed integral with the ring 26, and is 40 designed to be maintained in such contacting relation at all times by a retractile coil spring 36 connecting the ring 26 and the free end of the arm 38.

Shafts 4 and 18, being joined to each other, 50 rotate together as a consequence. Collar 19, as well as the mechanism carried thereby, rotate with the shaft 18. At one point during a complete revolution of the apparatus the outer end of the lever arm 32 will engage an obstruction, as 55 a stationary pin 37 protruding from the plate 7. Continued rotation of the apparatus will overcome the resistance offered by engagement of pin 37 and lever arm 32, but such resistance will be overcome only by arcuate movement of the lever arm 32 which, in turn, imparts slight rotary movement to the shaft 31 against the tension of the compression spring 33 and the tension of the latter is thereby increased. The slight rotary movement of the shaft 31 moves the arm 38 and 60 its roller 34 arcuately in a direction away from the lever 35, but the roller is prohibited from breaking contact with the lever 35 because the retractile coil spring 36 moves the ring 26 and its lever 35 in the same direction to compensate for 65 any retraction of the arm 38. As the arm 38 retracts arcuately, the roller 34 will travel outwardly toward the outer extremity of the lever 35 and the angularity of said lever will be altered.

As the lever arm 32 moves out of contact with 70 its engaging stationary pin 37 during continued

rotation of the apparatus, the force exerted on the compression spring 33 is instantly released and in recoiling the spring violently forces the parts to assume their original positions. In returning to original position, the arm 38 and roller 34 kick the lever 35 so as to spin the ring 26 at a speed much greater than the speed of the shaft 18. During this increase in speed, the cylindrical rollers 28 become wedged in the serrations of the lower end of the sleeve 23 and, in 10 the manner of a clutch, the rapid rotary movement is transmitted to the sleeve 23 and its top 22 so that the latter is freely rotated independently of and at a speed greater than the remainder of the apparatus. A spinning impulse of the 15 character described is imparted to the top during one complete revolution of the shaft 18.

A plurality of radially disposed and spaced pins 40 project outwardly from the periphery of the top and the spaces between each pin are consecutively numbered. A collar 41 is fixed to the shaft 18 above the sleeve 23 and is adapted to rotate therewith. An arm 42 extends outwardly from the collar and has a pointer indicator 43 and a flap 44 provided on its outer end. Being 20 affixed to the shaft 18, the arm 42 will rotate therewith about the top, which latter, as hereinbefore described, is also rotating at a greater speed. The person holding the number corresponding to the number on the top at which the 30 indicator points when movement of the entire apparatus ceases is accorded an award. For instance, the respective seats of the passenger cars may be numbered to correspond with the numbers on the top. The person occupying the seat 35 number on which the indicator stops may be awarded a free ride.

Supported by a collar 45 attached to the shaft 18 is the hub 46 of a canopy for the apparatus, the hub being freely rotatable on said shaft. Radial 40 arms 47 extend outwardly from the hub 46 and the outer ends of the radial arms are joined together by a rim consisting of a plurality of flat faces 48. Advertising matter may be carried by each of the flat faces 48.

Rotation is imparted to the canopy by a plurality of equally spaced pins 49 which depend from the hub. Two of the parallel tie rods 16 are connected by a transverse brace 50, as shown in Fig. 4 and in detail in Fig. 10. The brace 49 has 50 extending therefrom an integral lug 51 carrying an appropriate pawl 52. During operation of the apparatus, the pawl 52 will engage one of the depending pins 49 of the canopy as the tie rods 16 are being rocked to freely revolve the canopy on 55 the shaft 18, the canopy preferably being rotated in a direction opposite to that in which the passenger cars and the top are being rotated, the direction of rotation of the canopy being dependent upon whether the lug 51 and pawl 52 are 60 located on the brace 49 at one side or the other of the shaft 18.

The passenger cars 17, herein shown to simulate miniature airplanes, are preferably suspended from the arms 15 by yoke-like bails 53. 65 The lower ends of each bail is connected by an axle 54, and the cars 17 are pivotally borne thereby by means of lugs 55 which encircle the axle 54. Fixed collars 56 prevent shifting of the car on the axle. A leaf spring 58, connected to 70 the axle midway between its ends, exerts equal pressure on the forward and rearward portions of the car to normally maintain the latter in a horizontal plane.

A manually operable lever 70, pivoted to the 75

side of the car interiorly thereof, has its lower end pivoted to the axle 54 and extends upwardly therefrom interiorly of the car through an aperture in the floor, and projects upwardly in front of one of the seats 71 of the car. If the upper end of the lever is pulled rearwardly by the occupant of the seat, a depressing force will be exerted upon the car rearwardly of the axle and the front of the car will be elevated and the rear 10 of the car will be lowered so as to simulate an airplane rising for altitude in flight. Likewise, if the lever is pushed forwardly, a depressing force will be exerted upon the car forwardly of the axle and the front of the car will be lowered and the rear 15 of the car will be elevated so as to simulate an airplane losing altitude in flight. Such forward and rearward tilting of the car is limited by a pin 72 fastened to one of the yoke arms of the bail, the inner free end of the pin being received 20 within an arcuately shaped slot 73 provided in the side of the car.

Each car is preferably equipped with a motor driven propeller 74 operated by the occupant of one of the car seats 71. The propellers 74 may, 25 if desired, be utilized to drive the apparatus.

An appropriate housing (not shown) encases the track, axles, rollers, and similar unsightly mechanism. Likewise, the pedestal base may be

encased to conceal the operating mechanism housed therein.

What is claimed is—

1. In an amusement riding device, a pedestal base, an undulated circular track borne by said pedestal base, a driven shaft extending vertically through the center of said track, axles attached to said shaft intermediate their opposite ends and rockable about pivot pins connecting said axles to said shaft, rollers carried by the opposite 5 ends of each axle and adapted to travel over said trackway, and a supporting arm for a passenger car attached to each axle at a point adjacent its outer end but inwardly of said track.

2. In an amusement riding device, a pedestal 15 base, an undulated circular track, a driven shaft extending vertically through the center of said track, an axle having an aperture intermediate its ends encircling said shaft and attached to said shaft by a pivot pin, said axle being vertically 20 rockable about said pivot pin, rollers carried by the opposite ends of said axle and adapted to travel over said track, and a supporting arm for a passenger car attached to said axle at a point adjacent each of its opposite ends but inwardly 25 of said track.

RAYMOND R. WALKER.
GEORGE S. HAHNE.
